UNITED STATES PATENT OFFICE

2,094,201

SOUND RECORDER AND REPRODUCER

Max Bender, Los Angeles, Calif., assignor, by
mesne assignments, to United Acoustigraph
Corporation, a corporation of Nevada

Original application July 8, 1933, Serial No.
679,465. Divided and this application Decem-
ber 27, 1934, Serial No. 759,345. Renewed Jan-
uary 15, 1937

8 Claims. (Cl. 274—38)

This application is a division of my application
Serial No. 679,465, filed July 8, 1933.

This invention relates to a recording and re-
producing of sound, and has for its object an
improved apparatus and method for recording
sound in the form of a groove in relatively hard
material, such for example, as celluloid or motion
picture film. A further object is to provide an
improved form of cutting stylus.

10 The form of stylus herein disclosed is formed
with a curved cutting edge against which the film
is moved with the result that the sound groove
is formed by the cutting away and removal of a
portion of the film in the form of a fine thread.

15 Other objects and advantages of my invention
will appear from the following description taken
in connection with the accompanying drawing,
wherein:

Figure 1 is a vertical central sectional view,
20 partly in elevation of a sound recorder and re-
producer embodying one form of my invention;

Figure 2 is a greatly enlarged side elevation of
an improved form of a cutting stylus; and

Figure 3 is a sectional view taken on the line
25 3—3 of Figure 2; and

Figure 4 is a bottom plan view of the structure
shown in Figure 2.

Referring more particularly to Figure 1 of the
drawing, reference character 10 represents an
armature pivoted in bearings, one of which, 11,
30 is shown, which armature is adapted to be vi-
brated by an electro-magnet not shown. When
the apparatus is used for recording, the electro-
magnet will carry currents which vary in ac-
cordance with variations of the sound to be re-
corded. The armature 10 is formed with two
35 downward extensions 14 and 15 carrying respec-
tively a reproducing stylus 16 and a recording
stylus 17 adapted for engagement with the sur-
face of a film 20. In recording, the film 20 is
40 moved in the direction of the arrow over an anvil
21 which is formed, at the point of engagement
of the film with the cutting stylus, with a rela-
tively sharp curved surface. Figure 1 shows the
45 structure greatly enlarged, the curved upper por-
tion of the anvil for use with the usual motion
picture film having a radius less than an inch.

Referring to Figures 2 to 4, the recording stylus
17 is cemented into an opening 22 in the lower
50 end of the armature extension 15. The stylus,
which is of hard material such as sapphire or dia-
mond, consists of a cylindrical shank 24 which
is tapered as indicated at 25. One side of the
55 tapered surface is ground away to form a con-
cave tapered cutting surface 26 of the stylus.

This surface, in the position of the recorder
shown is an upper surface and beneath this sur-
face the taper is ground away to form two lower
concave surfaces 27 leaving between them a por-
tion 28 of the original tapered surface 25. The
5 effect of grinding or under-cutting to form sur-
face 27 is to sharpen the curved edge 30 at op-
posite sides of the axis of the stylus where the
upper surface 26 meets the lower surface of the
stylus. As the tapered surface 28 is conical, it is 10
a comparatively simple operation to grind away
this surface to a proper depth. The angle a be-
tween the upper surface 26 and the portion 28 of
the tapered surface 25 should be between 25° and
40° maximum. The angle b as shown in Figure 15
3, between the surface 27 and the upper surface
26 should be between 20° and 30° maximum. I
find that by forming a stylus in this manner with
the angles above given, I not only secure sat-
isfactory cutting but there is sufficient material 20
back of the cutting edge properly to strengthen
the stylus and minimize the breakage. In mak-
ing a sound groove of the lateral cut type, the
angle between the surface 28 and the tangent
25 to the film at the cutting point should be approxi-
mately 25°.

It will, of course, be understood that during
the recording operation, the stylus is vibrated by
the armature 10 or other actuating means, in ac-
cordance with sound waves to be recorded and 30
the recording action is not a scraping or an in-
denting action on the film but a cutting action.
The stylus as described makes a clean cut in the
film, removing therefrom a fine thread of the film
material.

35 While in the type of recorder shown, the record
groove is of the lateral type, the form of stylus
disclosed may also be employed for cutting a
groove of the hill and dale or vertical type.

Having now described my invention, what I 40
claim and desire to secure by Letters Patent is:—

1. A recording stylus comprising a shank ta-
pered at one end with the tapered surface cut
away at one side to form with the tapered sur-
face a curved cutting edge at the end of the 45
shank, and the side portions of said edge being
sharpened.

2. A recording stylus comprising a shank ta-
pered at one end with the tapered surface at one
side cut away to form a second tapered, cutting, 50
surface joining the first named tapered surface
in a curved edge, and having said edge under-cut
to sharpen the side portions of said edge.

3. A recording stylus having a shank formed
with a conical inclined surface cutting said shank 55

at one end and a second inclined surface cutting said shank at said end and located on the opposite side of said shank to said first named surface and meeting said first named surface in a short 5 cutting edge, and two side surfaces at opposite ends of said cutting edge, being inclined to both said first and second named surfaces and forming with one of said first and second named surfaces sharp continuations of said cutting edge.

10 4. A recording stylus having a shank formed with a conical inclined surface cutting said shank at one end and a second inclined surface cutting said shank at said end and located on the opposite side of said shank to said first named surface 15 and meeting said first named surface in a short cutting edge, and two side surfaces at opposite ends of said cutting edge, and inclined to both said first and second named surfaces and forming with one of said first and second named surfaces 20 sharp continuations of said cutting edge, the angle between said first and second named surfaces being between 25° and 40°, and the angle between each of said last named surfaces and said second named surfaces being between 20° and 25 30°.

5. A recording stylus comprising a shank tapered to form a conical surface at one end with the conical surface cut away at one side to form with said conical surface a curved cutting edge, and 30 portions of said edge being sharpened by cutting away the conical surface at opposite sides.

6. A recording stylus formed at one end with two oppositely inclined surfaces meeting in a

cutting edge, and the material being also cut away to form curved extensions of said edge at opposite ends of said edge.

7. The method of cutting a sound groove in a hard flexible member by means of a stylus comprising a shank tapered at one end with the tapered surface cut away at one side to form a second tapered cutting surface joining the first named tapered surface in a curved edge and having said edge undercut to sharpen the side portions of said edge, which method consists of maintaining said stylus with said tapered surface at the cutting edge at an angle of approximately 25° to the tangent to the flexible material at the cutting point, moving said material 15 against said edge and causing said stylus to vibrate in accordance with sound waves to be recorded.

8. Means for cutting a sound groove in a hard flexible member, a stylus comprising a shank 20 tapered at one end with the tapered surface cut away at one side to form with the tapered surface a curved cutting edge and having said edge undercut to sharpen the side portions of the edge, means for guiding a flexible member against said 25 edge, means for holding the stylus with the edge penetrating the surface of said flexible member and with said tapered surface at the cutting edge at approximately 25° to the tangent to the surface of the flexible material at the cutting point 30 and means for vibrating the stylus in accordance with the sound to be recorded.

MAX BENDER.
